APPARATUS FOR EDGING SHEET METAL
BLANKSJoseph Aneiros, Brooklyn, N. Y., assignor to E. W.
Bliss Company, Brooklyn, N. Y., a corporation
of Delaware

Application November 7, 1941, Serial No. 418,219

4 Claims. (Cl. 153—16)

This invention relates to improvements in a method and apparatus for making can bodies from sheet metal blanks and is more particularly concerned with the edging operation by which hooks are prepared on two edges of the blank which are then brought into a position to face each other and are interlocked to form the side seam of the can.

In edging can body blanks the hooks prepared on the blanks depend in their shape on the type of seam which it is intended to use in the completed can. The type of seam in turn depends on the subsequent use of the can. One of the most popular seams is the lock-and-lap seam used in making sanitary foodstuff cans. In forming the hooks for this type of seam one edge of the blank is bent back in a downward direction whereas the edge later to face the first one is bent back in an upward direction, the two hooks thus formed being capable of interlocking and overlapping. Another seam widely used is the Mennen seam, generally applied to powder cans of different types. This seam is made from a blank having a substantially U-shaped hook on one edge, the U having converging shanks, which are adapted to engage a hook-shaped edge formed oppositely thereto on the blank.

Can body makers heretofore used have embodied an edging station provided with tools for turning out blanks which would make one definite type of seam. If it was desired to manufacture cans with another type of seam the edging station had to undergo a complete rebuilding which involved considerable work and stopped the operation of the machine during a substantial change over period.

These difficulties in switching from one type of production to another have proved to be a great inconvenience in modern general line can manufacture, where machines are continuously run to capacity during certain periods.

The principal object of the present invention is to overcome the above disadvantages by providing the edging station with tools capable of being easily adapted to make the hooks of blanks in one way or another according to the type of seam chosen for a certain batch of cans, without compelling the operator to make changes in the general set-up of the machinery involving considerable time and labor.

In carrying out my invention I provide an edging station for a can body maker with two edge forming members, one of which is capable of shaping one edge of the blank into the U-shaped hook later to form the Mennen seam, while the

other member is adapted simultaneously to shape the hook engaging therewith on the other edge of the blank. By a change in the first-mentioned members the nature of which will be explained more fully hereinafter, I am able to achieve the above-mentioned object of adapting the mechanism as a whole to turn out blanks with edges for a lock-and-lap seam, without changing the mechanism as a whole on either side of the station.

10 To the accomplishment of the foregoing and related ends, said invention, then, consists of the means hereinafter fully described and particularly pointed out in the claims; the annexed drawings and the following description setting forth in detail certain means illustrating, however, but one of the various forms in which the principle of the invention may be used.

In said annexed drawings:

Fig. 1 is a side elevation of the edging station 20 when set for making the Mennen seam;

Fig. 2 shows an edging member, in the form of a lever, on an enlarged scale;

Fig. 3 is a side elevation of the same station when set for making the lock-and-lap seam; and

25 Fig. 4 illustrates the edging member shown in Fig. 2 in a different position.

Referring more particularly to Fig. 1, the machine comprises a frame 10 supporting an operating table 11 to which the blank B is fed from a preceding operating station in a known manner. Each side of the machine carries a bracket, the so-called edger bracket, the one on the left-hand part of the machine being indicated by 13, the right-hand one by 14. Bracket 13 carries a pressure shoe 15 having a pressing foot 16 rigidly attached thereto which serves for clamping the blank during the edging operation and the foot 16, preferably, has a beveled surface 16^x which may at the same time cooperate with the edging tool 23 in forming a hook on the blank.

30 Bracket 13 carries a pressure shoe 15 having a pressing foot 16 rigidly attached thereto which serves for clamping the blank during the edging operation and the foot 16, preferably, has a beveled surface 16^x which may at the same time cooperate with the edging tool 23 in forming a hook on the blank. This shoe is pivotally mounted on a pin 21 in the edger bracket 13. The upper end of the pressure shoe 15 is slidably and pivotally connected at 8 in a horizontal slot 28 of a crosshead 29, the horizontal slidability being provided in the connection at 8 to permit the conversion of vertical reciprocatory motion of the crosshead 29 into oscillatory motion of the pressure shoe 15 and to permit automatic or self-readjustment of the said parts

edging tool 23 rigidly attached thereto by means of bolts 24^a. The front edge of the tool 23, preferably, is shaped to cooperate with beveled surface 16^a of the pressing foot 16 in bending the plain hook for the Mennen seam. The edging lever is pivotally mounted on pin 21 and the end of the arm remote from the edging tool is pivotally connected as at 25 to a turnbuckle comprising a threaded tube 26 and two end portions 24 and 27, threadingly fitted thereto so that the length of the turnbuckle may be adjusted as required. The lower adjustable portion 27 of the turnbuckle has an extension 30 pivoted at 31 to one side of a bell crank 40, whose other arm 40^a is pivotally connected at 41 to an eccentric 42.

The edger bracket 14 pivotally supports a pressure shoe 12, at point 12^a at the right-hand side of Figs. 1 and 2, said shoe having a pressing foot 17 rigidly fastened thereto. This pressing foot serves on the one hand to hold down the blank during the edging operation, and on the other hand it has a die formed therein for shaping the U-formed hook of the Mennen seam which cooperates with the edge formed on the left hand side of the blank, as shown in Fig. 1. For this purpose a groove with sides 18, 18' is provided in said foot 17 which cooperates with two edging tools 19 and 20. The latter are mounted on slides 32 and 33 respectively, which are connected to dog levers 34 and 35 capable of operating the slides in timed relation. As slide 32 is moved inwardly, the U-shaped hook is formed on the right-hand edge of the blank and while the slide 32 is retracted, slide 33 is advanced, bending the right-hand shank of the hook inwardly to insure the locking engagement with the hook on the opposite edge at the time when the seaming operation takes place. Since the formation of the hooks for the Mennen seam is known in the art it is unnecessary to describe it in further detail.

Pressure shoe 12 is slidably and pivotally connected at 9 with one of its ends in a slot 36 of the crosshead 29, in much the same manner and for much the same reasons as hereinbefore recited in connection with pressure shoe 15 on the left-hand side of the machine.

For carrying out the edging operation in the timed movements of parts mentioned above the machine is provided with a main shaft 43 continuously rotated by suitable means. Upon said shaft four eccentrics are mounted adapted to actuate the edging members on both sides of the machine. Fig. 1 shows eccentric 42 for actuating the edging lever 22 at the left-hand side and eccentric 44 from which a connection leads to an arm 49 adapted to actuate pressure shoe 12 for clamping down the blank B. Fig. 3 shows these two and a third eccentric 45 which actuates slide 32 and the edging tool 19 thereon. The fourth eccentric is not visible in the drawings, since it lies behind the others in close proximity thereto; it serves for actuating slide 33 and the edging tool 20 thereon. Finally a cam 46 is mounted on shaft 43 and serves for operating crosshead 29.

The manner in which these members drive the forming elements and clamping means on both sides in timed relation will be described below.

As already mentioned the slides 32 and 33 are actuated by two pairs of dog levers 34 and 35 respectively, one of each pair being seen in the drawings. For accommodating said levers the slides are each provided with two elongated openings for receiving the knobs of said dog levers.

Thus slide 32 has a pair of openings 61 formed therein to receive knobs 62 of the two levers 34 carried by a common hub 69 which turns on a shaft 70. Hub 69 is furthermore provided with a forked arm 71 to which a longitudinally adjustable connecting rod 72 is pivoted at 73. The other end of said connecting rod is attached to the strap of eccentric 45 (Fig. 3).

During each rotation of shaft 43 slide 32 is once reciprocated whereby the tool 19 is actuated to bend the U-formed hook in the groove of pressing foot 17 and is thereafter retracted.

The construction for advancing and retracting edging tool 20 is quite similar. Slide 33 is provided with two openings 67 for receiving the knobs 68 of the pair of levers 35. A common hub 63 of these levers turns on a shaft 64 and is provided with an arm 65 to which is journaled at 66 one end of an adjustable rod 75, the other end of which is attached to the strap of the eccentric which is not visible in the drawings. It is obvious that the slides 32 and 33 alternately perform reciprocating movements with each rotation of the shaft 43, assuming, of course, that the several mentioned eccentrics are fixed in proper angular positions on said shaft.

The mechanism for controlling the movement of crosshead 29 and actuating pressure shoes 15 and 12 comprises a roller 80 rotatably mounted on a pin 81 so as to ride in the groove 46' of cam 46. Pin 81 is carried by one arm 82 of a bell crank lever which is pivotally mounted on a pin 83 secured to the machine frame. The second arm 84 of the bell crank lever is pivotally connected at 85 to a connecting rod 87 whose other end is pivoted at 90 to one end of a lever 88 journaled on a pin 89 which is secured to the machine frame. The other end of lever 88 is pivoted by pin 30^a to the crosshead 29.

The driving mechanism operates as follows:

Owing to the action of cam 46, roller 80 is reciprocated in vertical direction. By the upward movement arm 82 is lifted and arm 84 depressed, this movement being transmitted to rod 87, thence to lever 88. As lever 88 is pulled down at the left-hand side, crosshead 29 is raised and the pressure shoes are lifted from table 11, thus allowing the blank to be brought into position for the edging operation. Meanwhile cam 46 has been turned for half of a rotation and roller 80 moves downwardly, causing the transmission members to travel in opposite directions and making crosshead 29 and therewith both pressure shoes 15 and 12 and the feet fastened thereto to descend and hold down blank B in clamping engagement. This clamping effect is reinforced on the right-hand side by the action of arm 49, of pressure shoe 12, which arm is pivotally connected to a connecting rod 77 at 50, said rod being attached at its other end to an eccentric 44 driven in unison with cam 46.

As soon as blank B is held down against displacement the edging tools become operative, the left-hand tool 23 being actuated from eccentric 42 over bell crank 40^a, 40, extension 30, turnbuckle 26 and edging lever 22, and the right-hand edging tools 19 and 20 being operated alternately by their associated dog levers 34 and 35 and the driving mechanisms connected thereto as described above. Thus tool 19 is actuated from eccentric 45 and tool 20 from the eccentric lying behind the others. The edging tools on the left-hand and right-hand sides are so timed that while tool 23 makes one stroke, tools 19 and 20 each

make one stroke, that is to say, the edging mechanism at the right-hand side of the machine accomplishes two forming operations to form and partially close the U-shaped hook, while the left hand side edging mechanism accomplishes the formation of the plain hook in a single forming operation.

I have so far described the machine as shown in Figs. 1 and 2 when it is set for forming hooks of the shape which will form the Mennen seam. Referring now to Figs. 3 and 4 I shall describe how the machine is made ready to turn out blanks for making plain lock-and-lap seam. For this purpose two resettings of the machine are made which will only take the operator a short time. On the left-hand side of the machine the edging lever 22 is disconnected at 21 and attached at 43, as shown in Figs. 3 and 4. This will bring the edging tool 23 to the position there shown and into cooperating relation with a beveled surface of a forming tool 16^a provided at the under side of operating table 11. Instead of a hook bent upwardly, one being bent downwardly will thus be produced by the cooperation of tools 23 and 16^a. Since by the change of attachment of edging lever 22 just described, the fulcrum of said lever has been lowered, the bell crank 40 is disconnected from the lower end of extension 30 and pivotally reconnected to the lower end of the threaded part 27 of the turnbuckle 26, thereby shortening the linkage between the bell-crank 40 and the edging lever 22. The transmission of movement remains the same as described above in connection with Fig. 1.

On the right-hand side of the machine the pressing foot 17 is exchanged for a foot 17^a having a beveled face 17^x which cooperates with the edging tool 19 on slide 32 to form on a blank a plain hook bent upwardly as required for interlocking with the hook bent downwardly which is shaped simultaneously at the left-hand side of the machine. When the machine is intended to produce the hooks for the lock-and-lap seam the slide 33 is made inactive and only slide 32 is maintained in operation. The two edging tools 23 and 19 are in this case operating simultaneously.

From the foregoing description it will be easily understood that according to the invention the improved machine is very well suited for modern can production allowing of almost instantaneous adaption of the device without any delay.

Other modes of applying the principle of my invention may be employed instead of the one explained, change being made as regards the means and the steps herein disclosed, provided those stated by any of the following claims or their equivalent be employed.

I therefore particularly point out and distinctly claim as my invention:

1. In apparatus for edging sheet metal blanks or the like, including a movable member adapted, when mounted in one operative position, to form, on a marginal portion of a blank, a hook extending toward one side of the latter, and adapted, when mounted in another operative position, to form, on the same marginal portion of such a blank, a hook extending toward the other side thereof; the combination of holding means having portions to coact with said movable member to form such hooks and for holding said blank

while leaving, free, a marginal portion thereof, and means for selectively carrying said movable member in either of said mounting positions whereby to adapt the apparatus, when in one mounting position, to cause formation of a hook, on the said marginal portion, extending only toward one side of the blank, and when in another mounting position, to cause formation of a hook on the same marginal portion extending only toward the other side of the blank.

2. In apparatus for edging sheet metal blanks or the like, including a movable member adapted, in one operative position, to form, on a marginal portion of a blank, a hook extending toward one side of the latter, and adapted, in an opposite operative position, to form, on the same marginal portion of such a blank, a hook extending toward the other side thereof; the combination of holding means for holding said blank while leaving, free, a marginal portion thereof, and plural means, arranged toward opposite sides of a blank, so held, for selectively carrying said movable member in either of said opposite operative positions whereby to adapt the apparatus selectively to cause formation of a hook, on the same marginal portion, extending toward one or the other side of the blank.

3. In apparatus for edging sheet metal blanks or the like, including a rockable member having a tool portion thereon adapted to engage a marginal portion of a blank and form a marginal hook thereon; the combination of means for gripping said blank including two oppositely arranged blank-forming portions at opposite sides of a gripped blank, and dual mounting means, disposed toward opposite sides of a gripped blank, for selectively carrying said rockable member, pivotally, in either of two operative positions in one of which the rockable member is adapted to coact with one of said blank-forming portions to form, on a marginal portion of a blank, a hook extending toward one side of the blank and in the other of which positions the rockable member is adapted to coact with the other of said blank-forming portions to form, on the same marginal portion of such a blank, a hook extending toward the other side thereof.

4. In apparatus for edging sheet metal blanks or the like, including a rockable member adapted to engage a marginal portion of a blank and form a hook thereon; the combination of means for gripping said blank, which means include beveled blank-forming portions converging, on opposite sides of a gripped blank, toward a marginal portion thereof left free by said gripping means, and dual pivotal mounting means for selectively carrying said rockable member at its fulcrum at either of two fixed pivot points one of which is adapted to pivot the rockable member to coact with the beveled face of a first of said blank-forming portions to form a hook on said free marginal portion of the blank, extending toward one side of the latter, and the other of which is adapted to pivot the rockable member to coact with the beveled face of a second of said blank-forming portions to form a hook on said free marginal portion of the blank extending toward the other side of the latter.

JOSEPH ANEIROS.
